UNITED STATES PATENT OFFICE

101,639

DESIGN FOR A COMBINED CHAIR AND TABLE

Lewis Larsen, Menominee, Mich., assignor to Heywood-Wakefield Company, Gardner, Mass.,
a corporation of Massachusetts

Application August 1, 1936, Serial No. 64,168

Term of patent 3½ years

To all whom it may concern:

Be it known that I, Lewis Larsen, a citizen of the United States, and a resident of Menominee, county of Menominee, and State of Michigan, have invented a new, original, and ornamental Design for a Combined Chair and Table, of which the following is a specification, reference being had to the accompanying drawing, forming a part thereof, in which the figure is a perspective view of a combined chair and table showing my new design.

I claim:

The ornamental design for a combined chair and table, substantially as shown.

LEWIS LARSEN.
